UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

METHOD OF AND APPARATUS FOR MAKING SPLINE-CARRYING MACHINE ELEMENTS.

1,333,071.

Specification of Letters Patent.

Patented Mar. 9, 1920.

Application filed December 23, 1918. Serial No. 267,991.

To all whom it may concern:

Be it known that I, ALVA J. FISHER, a citizen of the United States, residing at Evanston, in the county of Cook and State of Illinois, have invented certain new and useful Improvements in Methods of and Apparatus for Making Spline-Carrying Machine Elements, of which the following is a specification.

10 My invention relates to making a spline-carrying machine element, and provides a method and means for its production.

Machine elements that are to be splined to shafts are usually made of steel, machined 15 to provide the shaft receptive hole and the spline slot, and into said slot the separately-made spline must be accurately fitted, either with a drive fit or with provision for rivet-retention. Inherently these elements are 20 relatively expensive, even in quantity production. Generically such splined elements must be accurate in shaft-hole size and centering, in the location, extent of projection and size of the spline, and in firm anchor-

25 age of the spline in the element-body. Of course these machine-elements may take an unlimited number of external forms, sizes, and designs, and in a great number of instances the element to be produced is of a 30 character that might well have its body made of cast metal if the requirements as to the shaft-hole and the spline can be met in the cast article.

35 My invention is intended to provide for the making of an inexpensive, satisfactory spline-carrying machine-element having its body mainly a casting, providing a satisfactory and adequate method and means for the production of such article, and in general 40 my invention consists in the features hereinafter set forth and claimed pertaining to the method and means for production of such articles.

As a single instance, for purposes of disclosure, I have selected a splined clutch-element as the subject of illustration, (but without intent, of course, to limit my invention in its broader aspects to such specific article), and in the drawings, Figure 1 is a 45 perspective view, with parts broken away, showing the splined clutch element with a cast-metal body; Fig. 2 is an elevation, with parts in section, of a core element suitable to be employed in the manufacture of 50 the specific clutch member; Fig. 3 is a per-

spective detail of a sleeve; Fig. 4 is a perspective detail of a spline-member detached; Fig. 5 is a sectional view of a mold with an embedded pattern, and Fig. 6 is a similar section of the mold with the core, sleeve, and 60 spline emplaced therein.

In detail the particular element illustrated in Fig. 1 is a clutch member 10 adapted for sliding fit with a grooved shaft, and the body 11 of the member is shown as a 65 casting shaped to provide end heads 12 and an intervening reduced waist 13, each head having crown teeth or projections 14. The shaft hole 15 extends axially through the body and is faced with a liner 16, preformed to its cylindrical contour of specified diameter. Through a slot 17 in this liner and into the shaft hole 15 there projects a 70 spline-member 18, partly embedded in the body-casting, and coöperating with the liner 75 and the cast body so that the several parts mentioned are united with substantially the rigidity and permanency of an integral structure.

For the production of the specific article 80 thus illustrated one preferably employs a usual casting flask 20, a pattern 21 for giving shape to the sand-cavity; and a special core element 22 congruent, in part, with the pattern and designed for coöperation with 85 the sleeve 16 and spline 18 during the casting operation. This core element is so constructed that it may be removed subsequently to the completion of the casting.

Pattern 21, from its middle to the imaginary lines X, X (Fig. 5) is externally shaped to give the sand-cavity proper form for shaping the casting-body, and beyond said lines it preferably provides axial guide extensions 23. The core-element 22 has 90 heads 24 and 24' preferably of metal to constitute chill blocks, and these heads, corresponding in shape with zones 23 of the pattern, fit in the guide extensions of the cavity, as shown in Fig. 6. In the simple element 100 shown these two heads may be duplicates in external shape, and provided with confronting recesses 25 to give form to the clutch teeth 14 of the machine-element. One head 24 is axially removable from the core stem 26 that connects them, such head fitting snugly on a reduced stem-extension 27 in the end of which there is a chord-notch 28 to engage a transverse pin 29 insuring that 105 the removable head always goes on the core- 110

stem in the same position with its notches 25 in proper register with, or in desired angular relation to, the notches in the opposed fixed head 24'. The stem-extension 27 should preferably be of diameter less than that of the stem 26 by an amount at least equal to the intended projection of the spline 18 into the shaft hole, and for the reception of the spline a groove 30 is made 10 along the stem, one end of the groove opening through the shoulder 31 between the stem 26 and extension 27.

Before the core is put in the mold cavity, the sleeve 16 is placed on the stem 26, with 15 the slot 17 radially registering with the groove 30. The spline 18 is then placed in the registering slot and groove, so as to project through the former and rest on the bottom of the groove, these pre-formed parts 20 being all dimensioned and shaped for neat interfitting in the stated relation. The upper portion of the spline 18 projects above the level of the liner 16, to be invested by the cast material of the body 11. Specifically 25 the spline may be a steel bar with its ends turned up as at 18^a and with small ears 18^b struck out at the angles of the ends and longitudinal-bar of the spline. Thus the entire upper edge of the bar of the spline, 30 its laterally extending ears 18^b, and its radially extending ends 18^a, may all be invested with the cast metal.

When placed in the mold, the parts are in absolutely centered position, with the 35 spline most accurately located and positioned against displacement, so that all that remains to be done for completing the article is to effect the casting operation in usual fashion.

40 After the casting has been completed the machine-element is removed from the sand, the detachable head of the core pulled off, and the core stem withdrawn from the shaft hole. The external surfaces of the article 45 may be then treated in any way usual with the treatment of castings.

In the matter of cost, the manufacture of 50 splined machine-elements in this way effects very noteworthy saving. For the production of many classes of machine elements no machining whatever of the product is necessary. In none of them is machining of the shaft hole or spline requisite. The units thus produced are of greatest uniformity 55 and precision in the centering, size and straightness of the shaft holes and in the location, size and extent of projection of the spline. Spline anchorage is absolute.

60 The co-operation of the sleeve 16 with the spline 18 not only is of greatest efficacy in insuring in the finished product its requisite ability smoothly to interfit with a given size of shaft, but it has important bearing on manufacturing economy in the saving of 65 the core members against damage. The

relatively thin liner doubtless expands somewhat under the heat of the cast metal, and shrinks back to initial size with the cooling of the metal, but its shape and the support that is afforded it enables it to withstand the pressure due to the shrinkage of the cast metal, so that it does not, in practice, grip the core with sufficient tenacity to destroy the surface of the latter when the core is removed. 75

Of course it will be understood that the shape of the spline may be widely varied, and that contour-changes of the embedded portions of the spline may be made. For one instance, the up-turned ends 18^a which, 80 in the present illustration, advantageously coöperate with the thick head-portions of the cast body, might not be at all suitable to some articles, but other anchoring-shapes of spline bar may be employed with accord- 85 ant change in details of the mold, if need be; and in all such details it will be understood that, while certain features of my invention are claimed in detail for their specific advantages, many changes may be made with- 90 out departure from the spirit of my invention in its broader aspects, and within the scope of the appended claims.

I do not herein claim the splined element *per se*, as the same is claimed in my co- 95 pending application divided herefrom.

What I claim is:

1. The process of making splined machine-elements which consists in mounting on a suitable core a slotted liner and a pre-formed 100 spline extending through said liner and projecting outwardly therebeyond, investing said liner and spline in molten metal, and thereafter removing the core.

2. The process of making splined machine 105 elements which consists in disposing a pre-formed spline to extend through and inwardly and outwardly beyond a slotted liner and casting a body around the liner and the outwardly extended portion of the spline. 110

3. The process of making splined machine elements which consists in surrounding a slotted core with a slotted liner, mounting a preformed spline in the liner slot to project inwardly into the core-slot and outwardly beyond the liner, investing the liner and spline in molten metal and thereafter removing the core. 115

4. The process of making splined machine elements which consists in assembling, in a mold, a core having a spline space, a spline extending into and also outwardly beyond said space, and a liner encompassing a portion of the core and spline, molding molten metal around the liner and the outwardly 120 extended spline part, and thereafter removing the mold parts and core. 125

5. Means for coöperation with a mold in the production of spline-carrying cast-metal machine-elements comprising, in combina- 130

- tion, a separable core having a spline-receptive slot, a slotted liner interfitting with said core, and a pre-formed spline inserted through said liner slot into the core slot and having portions protruding beyond said liner, whereby a body may be cast around said core-carried liner and spline and these removed from the core when the latter is separated.
- 10 6. In combination, a mold affording a metal-receptive space, a core in the mold having a spline-receptive space, a slotted liner surrounding the core, a spline inserted through the liner slot into said core-space and protruding into metal-receptive space of the mold, whereby a body may be cast around the liner and spline and these removed from the mold and core.
- 15 7. In combination, a mold having a metal receptive cavity and extensions, a core hav-
- ing a slotted stem and heads that fit in said mold cavity extensions, said core being separable to permit of removal of parts encompassing said stem, a slotted liner on the stem, a pre-formed spline extending through 25 said liner and into the stem-slot and having portions protruding into the mold-cavity, whereby a body may be cast around said liner, the body and core removed and the core removed from the united body, liner 30 and spline.
8. In combination, a mold, means to support a slotted liner therein, and a spline extending through the liner-slot and projecting on both sides thereof, whereby a body 35 may be cast around the liner and spline, to permanently unite the body, spline and liner into a spline-carrying machine-element.

ALVA J. FISHER.
